(57) **CLAIM**

The ornamental design for a combined watch and band, as shown and described.

DESCRIPTION

FIG. 1 is a front elevation of a combined watch and band showing my new design;

FIG. 2 is a top plan view thereof;

FIG. 3 is a left side elevational view thereof;

FIG. 4 is a right side elevational view thereof; and,

FIG. 5 is a rear elevation thereof.

The bottom plan view is a mirror image of the top plan view.

The broken-line showing of FIGS. 1-5 are for illustrative purposes only and form no part of the claimed design.
